(57) **CLAIM**

The ornamental design for a grinder attachment for a stand mixer, as shown.

DESCRIPTION

The file of this patent contains at least one drawing/photograph executed in color. Copies of this patent with color drawing(s)/photograph(s) will be provided by the Office upon request and payment of the necessary fee.

FIG. 1 is a front-perspective view of a grinder attachment for a stand mixer according to our design;

FIG. 2 is a bottom-back perspective view thereof;

FIG. 3 is a front elevation view thereof;

FIG. 4 is a back elevation view thereof;

FIG. 5 is a right side elevation view thereof;

FIG. 6 is a left side elevation view thereof;

FIG. 7 is a top plan view thereof; and,

FIG. 8 is a bottom plan view thereof.

Broken lines show portions of the article that form no part of the claimed design.

Dash-dot lines represent bounds of the claimed design and form no part of the claimed design.

The drawings are shown shaded with color depicting a metallic material with a reflective appearance, the particular color forming no part of the claim.
